Des. 226,138
Patented Jan. 23, 1973

226,138

BALLOT PUNCH

Kellog D. Fleming, San Francisco, Calif., assignor to
Diamond National Corporation, San Francisco, Calif.

Filed Apr. 14, 1971, Ser. No. 134,118

Term of patent 14 years

Int. Cl. D19—02

U.S. Cl. D74—1

FIG. 1.

FIG. 2.

FIG.3.

FIG.4.

FIG.5.

FIG.6.

FIG. 1 is a perspective view showing a ballot punch embodying the design of my invention;

FIG. 2 is a top plan view thereof;

FIG. 3 is a side elevational view of one side thereof;

FIG. 4 is a side elevational view of the other side thereof;

FIG. 5 is a right end elevational view, the left end being a mirror image thereof; and

FIG. 6 is a bottom plan view thereof.

I claim:

The ornamental design for a ballot punch, substantially as shown and described.
